UNITED STATES PATENT OFFICE.

OWEN TAYLOR AND CHARLES C. TAYLOR, OF HUNTINGTON, WEST VIRGINIA.

RADIANT BACK.

Application filed October 2, 1923. Serial No. 666,118.

To all whom it may concern:

Be it known that we, OWEN TAYLOR and CHARLES C. TAYLOR, citizens of the United States, residing at Huntington, in the county 5 of Cabell and State of West Virginia, have invented certain new and useful Improvements in Radiant Backs; and we do hereby declare the following to be a full, clear, and exact description of the invention, such as 10 will enable others skilled in the art to which it appertains to make and use the same.

The object of the present invention is the provision of a radiant back for furnaces, ranges and other heaters for cooking or 15 other required purposes, which may be molded easily of any suitable material, such as fire clay or metal and which may be produced at a relatively low cost.

Other objects and advantages will be apparent and suggest themselves as the nature 20 of the invention is understood.

While the drawings illustrate an embodiment of the invention it is to be understood that in adapting the same to meet different 25 conditions and requirements, various changes in the form, proportion and minor details of construction may be resorted to without departing from the nature of the invention.

30 Referring to the accompanying drawings forming a part of the application:

Figure 1 is an elevational view, partly in section, of a gas stove having the oven and burners provided with radiant backs embodying the invention,

Figure 2 is a detail sectional view on the line 2—2 of Figure 1,

Figure 3 is a front view of a radiant element,

40 Figure 4 is a sectional view of the radiant element on the line 4—4 of Figure 3,

Figure 5 is a sectional view on the line 5—5 of Figure 3,

Figure 6 is a top view of a radiant element,

Figure 7 is a detail sectional view on the line 7—7 of Figure 1 showing the parts on a larger scale,

Figure 8 is an elevational view of a radiant element forming part of a circular back, and

Figure 9 is a view similar to Figure 5 of a modification.

Corresponding and like parts are referred 55 to in the following description and desig-

nated in the several views of the drawings by like reference characters.

The cook stove illustrated has radiant backs applied to the baking and warming oven and to the burners for heating utensils for cooking and other purposes. The ovens have the radiant backs applied to opposite sides whereby to equalize the heat and the burners have circular backs associated therewith. The radiant backs whether straight, circular or curved comprise elements substantially as illustrated. The elements comprising the straight back have their edges straight, as indicated most clearly in Figure 2. The elements comprising the circular or curved back have their edges inclined, as indicated most clearly in Figure 7, to admit of the elements when arranged assuming a circular or curved outline.

The radiant elements are preferably of sectional formation to admit of their ready molding. The elements are elongated and when assembled occupy a vertical position with the edges of adjacent elements in contact. Each element comprises a rear section 1 and a front section 2, the sections being jointed to prevent displacement. The rear section 1 is hollow and the space is closed at the top and open at the bottom 85 as indicated most clearly in Figure 4. The back wall of the space is formed with a series of concavities, as indicated most clearly at 3 in Figure 4. The ridges or crests separating the depressions have points 4 extending forwardly therefrom to assist materially in radiating the heat. The vertical edge portions of the sides are grooved as indicated at 5 to receive tongues 6 adjacent the edges of the front section 2 and these meshing tongues and grooves provide joints to maintain the sections 1 and 2 in proper 90 position.

The front section may be straight, as shown most clearly in Figures 5 and 6, or curved as illustrated in Figure 9, but in each instance it is of open or latticed formation to provide an escape for the heat which is radiated by the corrugated or fluted backs and the points projecting therefrom. As shown clearly in Figures 3 and 8 the front sections comprise a plurality of cross bars 7 which result in the formation of diamond-shaped openings 8 and opposed triangular shaped openings 9. The crest or ridges 95

and the points 4 are disposed opposite the major axis of a diamond-shaped opening 8 whereby to secure a maximum discharge for the radiant and deflected heat.

5 As indicated in Figure 7, the radiant elements are of sector formation and of such relative size as to occupy and form a circular outline when assembled. The radiant elements may be molded of fire 10 clay or other suitable material.

Having thus described the invention, what we claim is:

1. A radiant back comprising upstanding segments forming an endless figure, each 15 segment having a front portion and a back portion in separable relation and radial side walls, the adjacent side walls being in contact with each other, an interfitting means between the side walls and both portions of each segment whereby the same 20 cannot accidentally turn relatively to each other when assembled.

2. A radiant back comprising upstanding segments forming an endless figure, each segment having a front portion and a back 25 portion in separable relation and radial side walls, the adjacent side walls being in contact with each other, an interfitting means between the side walls and both portions of each segment whereby the same 30 cannot accidentally turn relatively to each other when assembled, the front portion having openings for radiation of heat, the back being provided with a series of relatively long vertical concavities of substantially the width of the interior of the back portion, the back portion at each junction of adjacent concavities having transverse rows 35 of forwardly extending points.

In testimony whereof we affix our signatures.

OWEN TAYLOR.
CHARLES C. TAYLOR.
